UNITED STATES PATENT OFFICE

JAMES M. WEBSTER, OF NEW YORK, N. Y.

HANGAR FOR AEROPLANES AND THE LIKE

Application filed March 8, 1930. Serial No. 434,826.

The present invention relates to aeroplane hangars and more particularly to an improved hangar and associated equipment for fire protection and for storing and removing 5 aeroplanes rapidly.

The economic considerations involved in the problems of transporting passengers, express and mail by air have brought into existence a class of aeroplane commonly spoken 10 of as a "transport 'plane". Such aeroplanes are usually of the multi-engined monoplane type with large pay load capacities and may be either land 'planes, sea 'planes, flying boats or amphibians. The large wing area required involves a correspondingly large wing 15 span. This, together with their great weight, introduces certain problems into their handling, fire protection, and storage at the airport, which this invention seeks to solve, 20 one of the objects being to produce a hangar for this type of 'plane which will combine a maximum efficiency in the use of storage space, ease in handling during daily operation and a system of salvage for the 'planes, 25 in the event of fire, designed to reduce insurance rates by minimizing the fire hazard.

While the hangar structure proper may be of the conventional type consisting of 30 steel columns, roof trusses, roofing, brick side walls, and factory type sash, it has been found that an economy in the weight of the trusses may be effected by sliding the 'planes into the hangar with the longitudinal axis of the fusilage parallel to the chord members 35 of the roof trusses. This follows from the fact that the length of the fusilage is usually the least overall dimension and also from the fact that the weight and consequent cost of the roof truss varies nearly substantially 40 as the square of the span.

Due to the fact that the aeroplanes stored in the hangars have a substantial amount of gasoline in their storage reservoirs, and due 45 to the fact that oil and other inflammable products are almost certain to be dripping from various portions of the 'planes, fires which are extremely hazardous occur frequently. The mechanics and other persons working upon or handling the 'planes use 50 cotton waste for wiping off the oil and this

waste is frequently permitted, through carelessness or otherwise, to remain within the hangar. The products with which the waste is saturated, being highly volatile, may be ignited by spontaneous combustion to cause a 55 fire which would, of itself, be inconsequential if it would not spread to the aeroplane. If the aeroplanes take fire, the gas tanks are likely to explode and the resulting fire destroys both the aeroplanes within the hangar 60 and the hangar itself. To avoid such contingencies, elaborate sprinkler systems have been devised to spray the 'planes with water or chemicals when fires occur. Due to the size of the hangar, such sprinkler systems are 65 extremely expensive and represent a substantial part of the cost of the hangar. The arrangement, heretofore, of 'planes within the hangars has increased substantially the size 70 of the hangar for storing a given number of 'planes.

The present invention aims to eliminate or minimize the above difficulties and, at the same time, to reduce the size of the hangars and decrease the cost thereof. The above advantages are achieved in the present embodiment by drastic reduction of the expensive 75 sprinkler systems heretofore utilized, by proper arrangement of the aeroplanes to reduce the size of the hangar, and by the automatic removal of the 'planes from the hangar under certain conditions. While the invention is particularly applicable to transport 80 hangars, it will be understood that many of its advantages may be utilized otherwise and that the invention is not to be considered as 85 thus limited.

An object of the invention is to reduce the size and cost of aeroplane hangars and particularly hangars for storing transport aeroplanes. 90

Another object of the invention is to minimize fire hazards in aeroplane hangars and the like. 95

Another object of the invention is to facilitate storing and removal of large aeroplanes from hangars.

Another object of the invention is to provide means for automatically removing the 100

aeroplanes from a hangar when a predetermined condition exists within the hangar.

Another object of the invention is to provide automatic means for opening the doors 5 of a hangar so that the aeroplanes therein may be removed when a predetermined condition exists within the hangar.

A further object of the invention is to reduce the cost of aeroplane hangars by reducing the amount of, and in fact eliminating 10 the major part of, the expensive sprinkler systems heretofore used and, at the same time, to decrease the fire hazard.

Other and further objects of the invention 15 will be obvious upon an understanding of the illustrative embodiment about to be described or will be indicated in the appended claims, and various advantages not referred to herein will occur to one skilled in the art 20 upon employment of the invention in practice.

A preferred embodiment of the invention has been chosen for purposes of illustration and description and is shown in the accompanying drawings, forming a part of the 25 specification, wherein.

Fig. 1 is a perspective view of a double hangar, the 'planes of one side being partially removed;

30 Fig. 2 is a top plan view of one side of the hangar, that is a single hangar, with the roof removed to illustrate the position of the aeroplanes therein, the other side of the hangar being omitted to avoid duplication;

35 Fig. 3 is a sectional view along the line 3—3 of Fig. 2;

Fig. 4 is a diagrammatic view illustrating the power connections for storing and removing the aeroplanes;

40 Fig. 5 is a side elevational view of the parts shown in Fig. 4;

Fig. 6 is a diagrammatic view illustrating one form of automatic means for removing the aeroplanes when a predetermined condition exists within the hangar;

45 Fig. 7 is a top plan view of another form of door which may be utilized for the hangar; and

50 Fig. 8 is a side elevational view of the door shown in Fig. 7.

Referring again to the drawings, and more particularly to Figs. 1 to 3, there is shown a hangar 1 which is particularly adapted for large transport aeroplanes, although many of its features are advantageous in other constructions. The sides 2 and roof 4 of the hangar may be constructed in the usual manner; for example, the sides may be of brick or concrete and the roof may be supported by a steel truss construction, as indicated.

A detailed description of these parts is not necessary because they are well known and are not a part of the present invention. Pairs 65 of tracks 7 and 8 are provided adjacent and

substantially parallel to each of the side walls 2. Mounted upon each pair of tracks are suitable trucks, indicated at 9 on the tracks 7 and at 10 on the tracks 8. These trucks, 9 and 10, are sufficiently strong to support 70 transport aeroplanes; preferably, the landing wheels of the aeroplanes are placed on one or more trucks resting upon one pair of rails and the tail of the aeroplane is permitted to rest upon another truck on the other pair of rails. In this way, simultaneous movement of the trucks on the respective pairs of rails will move the aeroplane out of the hangar or into the hangar.

In order to minimize space and to reduce 80 the size of the hangar adjacent aeroplanes 11 are mounted with their front portions on opposite sides of the hangar or facing in opposite directions. The purpose of positioning the aeroplanes in this manner is to permit 85 them to dovetail together so that the wings of one 'plane will extend over the tail of another 'plane. The wings of the aeroplane are, of course, the widest portion thereof and by overlapping the wings a substantial saving of 90 space is achieved. It will be understood that beneficial results could also be attained by mounting one aeroplane on trucks higher than the trucks mounting the other aeroplane, whereby the wings would be overlapped one 95 above another. It is preferred, however, to arrange the aeroplanes as indicated more particularly in Fig. 2 of the drawings.

A suitable partition 14 may be provided intermediate the two inner aeroplanes to separate them and to divide the hangar into a plurality of compartments, illustrated herein as four, thereby to prevent a fire in one compartment from spreading to the other. The partition is preferably substantially Z-shaped; that is, it has two transversely extending portions 15 and 16 connected by a longitudinally extending part 17. Other shapes can, of course, be utilized to achieve the same result. By having a plurality of 100 compartments housing the 'planes, the fire hazard and the insurance rates are reduced 105 materially.

A substantial part of the cost in the transportation of passengers by air is due to the 110 salaries or wages of the ground crew which must be maintained at the hangars for moving the large aeroplanes around and storing them. The use of highly paid aeroplane mechanics for moving ships is not only poor economy but also tends to disorganize their work on the necessary repairs always incident to the operation of a busy transport line. The present invention contemplates the reduction of such crews to a minimum by providing a construction which may be operated 115 by one person, either to store or remove one or more aeroplanes. The present handling of 'planes by crews who push the 'planes around, frequently strains or impairs some 120

125

part thereof and, hence, increases flying hazards.

The illustrative embodiment provides an apron 18 along which the pairs of tracks 7 and 8 extend. A suitable concrete flooring is provided adjacent the track so that the tops of the trucks will be flush with the flooring to permit the aeroplanes to be taxied off the apron under their own power. If desired, tractors may be utilized for this purpose. Where four aeroplanes are stored in a single hangar, preferably a door is provided at each side of the hangar with the apron 18 and concrete floor 19 extending from each of the doors. In order to avoid duplication in Fig. 2, the apron and its associated parts at the right side of the hangar have been broken away, its construction being identical with that shown on the left side of the hangar, including the cables and power operating mechanism. A description of one side of the single hangar will, therefore, serve equally well for the other side and also for the double hangar shown in Fig. 1.

At the end of the apron 18, a suitable source of power such as a motor 22 is provided, which rotates shaft 27 through a sprocket 24 on the shaft of the motor, chain 25, and sprocket 26 on shaft 27. The shaft 27 has mounted on each end thereof sprockets 29 and 30, connected by chains 31 and 32 with sprockets 33 and 34 respectively, on shaft 35. Sprocket 33 and 34 are mounted upon suitable sleeves 36 and 38, which are free to rotate about the shaft 35 and have integral therewith drums 39 and 40. Cables 41 and 42 are mounted on drums 39 and 40 on the ends of shaft 35 and on drums or pulleys 44 and 45 respectively, at each end of shaft 46.

Cables 41 are operatively connected to the trucks mounting the aeroplane nearest the door and are also connected to the trucks upon which the door is mounted. The cables 42 are operatively connected to the trucks mounting the aeroplane adjacent the partition 14. Suitable brackets 52, with apertures 54 therein, are provided on the trucks through which the cables pass. Suitable lugs may be provided on the cables for engaging these brackets 52 to move the trucks in either direction. It will be understood, however, that any other suitable means may be employed for attaching the cables to the respective trucks mounting the door and the planes.

The connections between the cables and the trucks should be substantially rigid so that the trucks commence to move at the same time that the cables do to avoid sudden jars. If necessary, a suitable spring can be mounted between the bracket and the lug on each cable to cushion any such shock.

It will be noted that the sprocket wheels for driving the cables 41 are proportioned to move the cables at a greater speed than that of the cables 42. The purpose of this is to

move the door closing the hangar and the aeroplane adjacent the door at a greater speed than the aeroplane adjacent the partition 14. In this way, the aeroplanes, when they have reached the apron 18 or have reached their final position, are separated from each other substantially so that a fire in one will not endanger the other.

For convenience in removal and storage of the aeroplanes, the present invention contemplates the provision of an improved door 60, shown more particularly in Figs. 4 and 5, mounted upon suitable trucks running on the pairs of tracks 7 and 8. The door is illustrated diagrammatically in Fig. 5 as comprising a member 61, held in upright position by braces or trusses 62 mounted upon the trucks on tracks 7 and 8. The cable 41 is shown in operative relation to the trucks mounting the door for moving the door in the same manner and at the same speed that the outer aeroplane is moved. In this manner, when the motor is started for removing the aeroplanes, the door is automatically moved out with the aeroplanes and at the same speed that the forward aeroplane is moved.

Any suitable means may be utilized for locking the door in position and for automatically releasing the same. One form of device is illustrated diagrammatically in Fig. 5, which comprises a latch member 64 pivoted at 65 and normally hooked over the door, as indicated at 66. A suitable electro-magnet 67, which is connected by leads 68 directly across the power line for the motor, is adapted to lift the latch member 64 and release the door when the motor is started, and hold the latch member in ineffective position until the motor is stopped. In this way, the door is automatically released and automatically locked. It will be understood that any number of locking members 64 may be utilized to hold the door securely in position.

In Figs. 7 and 8, another form of door is indicated which is a sliding door comprising the sections 70, 71, 72 and 73. A suitable cable 74 passes around pulleys on these several sections and over the pulleys 75 and 76 to the latter of which a counter-weight 77 is secured. The counter-weight 77 is sufficient to open the doors when released. A suitable release mechanism, such as that indicated on the door in Fig. 7, may be utilized to open the door automatically by releasing the counter-weight when the motor is started to remove the aeroplanes from the hangar.

In order to reduce the fire hazard and to eliminate the necessity for elaborate and expensive sprinkler systems, there is provided, as shown more particularly in Fig. 2 of the drawings, a series of temperature responsive units. Generally described, such devices are adapted to operate on a rapid change in temperature, rather than at a predetermined temperature. They usually comprise reservoirs

for air or gas which have a bleed valve or aperture so that ordinary changes in temperature are automatically compensated for, but rapid changes in temperature are communicated to a suitable diaphragm which operates a suitable electric control. As indicated in Fig. 2, the several reservoirs 80 (illustrated as ten in number) are positioned about the hangar so that any substantial fire will cause one of these to increase substantially in temperature. A small pipe or tube 81, which may be encased in a larger pipe 82, connects with each of the five reservoirs 80 on one side of the hangar. A similar tube 83, encased in a larger pipe 84, connects with the five reservoirs on the other side of the hangar. The ends of the tubes 81 and 83 are joined by the encased tubes 79 and 85 which connect to electric releases 86 and 87 respectively, as indicated in Figs. 2 and 6. The electric releases 86 and 87 may be similar to those now on the market. These releases may operate control circuits to operate a suitable alarm to admit water to the sprinkler devices adjacent the doors and to supply power to the motor 22 for automatically opening the hangar doors and removing the aeroplanes. To avoid a detailed description of the various parts of the preferred control, a diagrammatic illustration of a control is shown more particularly in Fig. 6. The tube 79, encased in a larger pipe 88, has a bleed aperture 89 which compensates for normal changes in temperature but is inadequate to relieve abnormal changes. The tube 79 is connected to a hollow member 90 having a diaphragm 91 therein. Pressures in any one of the several reservoirs 80, caused by abnormal rates of increase in temperature, are communicated directly to the diaphragm 91. A pin 92 is attached to the diaphragm and is free to move with the diaphragm and is adapted to close the relay circuit 94 having a battery, or other source of current 95, therein. An increase in pressure in the system not relieved by the aperture 89, is communicated to the diaphragm 91 which forces the pin 92 outwardly and causes the bar 96 thereon to close the relay circuit 94. Closing the relay circuit operates a relay 97 to connect the main source of power 98 to the motor 22 through an automatic starter 99. This starts the motor and automatically opens the doors of the hangar and removes the aeroplanes. The closing of the relay circuit 94 also operates the bell 100, or other suitable alarm, and opens a suitable electrically operated water valve, indicated at 101, to admit water to the pipes 102 having outlets 104 in the floor of the hangar adjacent the door. Similar pipes may be provided in the ceiling of the hangar adjacent the doors. The purpose of these is to extinguish any fires in the vicinity of the doors and to prevent the aeroplanes from being ignited while

passing the vicinity of such fires during their automatic removal. By dragging the plane through a deluge or water curtain, any fire in the plane itself is extinguished before leaving the hangar. The cost of the pipes is relatively small due to the fact that only small parts of the hangar adjacent the doors are piped.

In the operation of the device, the aeroplanes are taxied onto the apron 18, or drawn thereon by means of a suitable tractor, and deposited on the trucks as indicated in dotted lines in Fig. 2. Thereafter, the switch 93 may be closed and any suitable starting device 103 utilized to start the motor 22, which rotates shaft 27 through sprockets 24 and 26 and chain 25. This, in turn, through the sprockets 29 and 30 (see Fig. 4) and chains 31 and 32, rotates the sprockets 33 and 34 and their corresponding drums 39 and 40. The cables 41 on drums 39 are operatively connected to the trucks supporting the door 60 and the outer aeroplane 11 to move them along the tracks 7 and 8 into the hangar, as indicated in full lines in Fig. 2. The door, when it reaches its closed position, is locked by means of the latch 64 and a suitable automatic mechanism, operated by the door, stops the motor. The cables are, likewise, connected to the trucks supporting the inner aeroplane to move it into or out of the hangar. In the same manner, the starter 103 may be operated to run the motor in the opposite direction to unlatch the door 60, and to move the aeroplanes out onto the apron 18. In such movement, the drums 39 and 40, being of different size, the aeroplanes are separated as indicated in dotted lines in Fig. 2.

In the event of fire in any portion of the hangar, the several reservoirs 80, or other suitable temperature responsive devices or one of them, increase in temperature and release air through tubes 79, 81, 83 and 85 into the hollow member 90 against the diaphragm 91, which flexes the diaphragm to close circuit 94, which operates the relay 97 and the fire alarm bell 100 so that the alarm is given and the circuit is automatically closed to start the motor 22 and the aeroplanes are removed and separated from the hangar. In addition, the relay circuit 94 operates an electrically controlled water valve to supply water to the pipes 102 to spray the portions of the hangar adjacent the doors.

When the door in Figs. 7 and 8 is utilized, the several sections 70, 71, 72 and 73 are permitted to open fully prior to substantial movement of the aeroplanes toward them. The aeroplanes, in passing out of the hangar, move through the automatic sprinkler system 104, which, in turn, puts out any fire in the vicinity of the door so that, in the event the fire started at the door, it would be extinguished before the aeroplanes have reached it.

It will be seen that the above invention provides a hanger of low construction cost where in the aeroplanes may be compactly arranged and fire hazards minimized. A single person may either store the aeroplanes or remove them from the hangar, which reduces substantially the ground crew ordinarily required. In case of fire, the aeroplanes are not only automatically removed from the hangar but are separated from each other so that when a fire starts in one 'plane it will not affect either the other 'planes or the hangar. If a fire starts in the hangar itself, the aeroplanes are removed before any substantial damage is done and the hangar, being quite large and being constructed of substantially fire-proof material, is not likely to be damaged. On the other hand, if one of the aeroplanes were to burn in the hangar, it would undoubtedly impair the structure and do considerable damage. The hangar and its associated parts operate automatically both to lock the door and release it, and likewise to open the door when the aeroplanes are removed. A single aeroplane may be removed by means of a suitable clutch which disengages the drum operating the cable attached to the trucks under the inner 'plane. The partition extending centrally of the hangar does not take up additional space and further reduces the fire hazard. The construction is simple in operation and is not likely to get out of order and occasion difficulties.

It is also evident that, by means of introducing the 'planes into the hangar as described, certain economies in the use of floor space may be realized by placing the wings and tail skids of adjoining 'planes at opposite sides of the hangar, as shown in Fig. 2. As various changes may be made in the form, construction and arrangement of parts without departing from the spirit and scope of the invention and without sacrificing its advantages, it is to be understood that all matter herein is to be interpreted as illustrative and not in a limiting sense.

Having thus described my invention, I claim:

1. In an aeroplane hangar, the combination of means for movably mounting aeroplanes, a source of power operatively connected to said means, and temperature responsive devices operatively connected to said source of power to remove said aeroplanes from the hangar.

2. In an aeroplane hangar, the combination of a source of power operatively connected to an aeroplane in said hangar, and temperature responsive devices for actuating said source of power when a predetermined temperature has been reached to remove said aeroplane from said hangar.

3. In an aeroplane hangar, the combination of a source of power operatively connected to an aeroplane in said hangar and adapted to remove said aeroplane from said hangar, and

temperature responsive devices adapted to actuate said source of power to remove the aeroplane when the rate of increase in temperature in a portion of said hangar increases beyond a predetermined maximum.

4. In an aeroplane hangar, the combination of trucks supporting aeroplanes, means operatively connected to said trucks to remove said aeroplanes from the hangar, means for holding the door to said hangar in closed position, and automatic devices for releasing said door when said first mentioned means is operated to remove an aeroplane from said hangar.

5. In an aeroplane hangar having a door, the combination of trucks adapted to support aeroplanes thereon, and means for moving said trucks and said aeroplanes out of said hangar, said means being adapted to move one aeroplane at a faster rate than another aeroplane to separate said aeroplanes.

6. In an aeroplane hangar, the combination of means operatively connected to said aeroplanes to remove said aeroplanes from the hangar, a source of power for said means, temperature responsive devices for rendering said source of power effective upon said means to remove said aeroplanes from the hangar, said means being adapted to separate the aeroplanes, thereby to prevent a fire in one 'plane from damaging another 'plane.

7. In an aeroplane hangar, the combination of a door mounted upon trucks, a source of power connected to said door, and temperature responsive devices adapted to render said source of power effective upon said door to open said door when a predetermined temperature condition exists in the hangar.

8. In an aeroplane hangar, the combination of a door, a source of power connected to said door, and temperature responsive devices adapted to render said source of power effective upon said door to open said door when a predetermined temperature condition exists in the hangar.

9. In an aeroplane hangar, the combination of a pair of tracks, trucks mounted upon said tracks, certain of said trucks being adapted to support an aeroplane, a door mounted upon other trucks, cables operatively connected to said trucks, and means for moving said cables at different rates of speed to separate certain of said trucks from other trucks.

10. In an aeroplane hangar, the combination of a plurality of compartments, a partition separating certain of said compartments, said partition being shaped to permit aeroplanes on the respective sides thereof to be dovetailed together to decrease the space required, means operatively connected to said aeroplanes for removing them from said hangar, and a source of power for operating said means to withdraw said aeroplanes from the opposite ends of said hangar.

11. In an aeroplane hangar, the combina-

- tion of a pair of aeroplanes in said hangar, devices operatively connected to said aeroplanes for removing them from said hangar, said devices being adapted to move the aeroplanes in opposite directions, a source of power for operating said means, and temperature responsive devices for rendering said source of power effective upon said means.
- 10 12. In an aeroplane hangar, the combination of trucks for mounting aeroplanes, means operatively connected to said trucks to remove said trucks from said hangar, said means being adapted to move certain of said trucks in one direction and other of said trucks in an opposite direction to separate said aeroplanes, and temperature responsive devices for actuating said means to remove said aeroplanes from the hangar when a predetermined temperature condition exists within the hangar.
- 15 13. In an aeroplane hangar, the combination of a plurality of trucks for mounting aeroplanes, means operatively connected to said trucks to remove said trucks and the aeroplanes from said hangar, temperature responsive devices adapted to release the doors to said hangar and to operate said means to remove said trucks and the aeroplanes from the hangar when a predetermined temperature exists within the hangar.
- 20 14. In an aeroplane hangar, the combination of a plurality of aeroplanes within the hangar dovetailed with respect to each other to decrease the storage space required, trucks for mounting said aeroplanes, a partition extending between certain of said aeroplanes to separate them, devices operatively connected to said trucks for removing them in a direction away from said partition to remove the aeroplanes from the hangar, temperature responsive devices for opening the doors of said hangar and operating said means to remove the trucks and aeroplanes from the hangar when a predetermined temperature condition exists therein.
- 25 15. In a device of the class described, the combination of a door, movable trucks for mounting said door, and automatic means for operating said door.
- 30 16. In an aeroplane hanger, the combination of sprinkler devices adjacent the door of said hanger, temperature responsive devices adapted to automatically cause the removal of the planes from the hangar, and means for causing said sprinkler devices to spray the portion of the hangar adjacent the door prior to and during the passage of an aeroplane therethrough.
- 35 17. In an aeroplane hangar, the combination of a water curtain adjacent a door of the hangar, and temperature responsive devices for causing said water curtain to spray the portion of the hangar adjacent the door
- when a predetermined temperature condition exists.
- 40 18. In an aeroplane hangar, the combination of a plurality of movable means for mounting aeroplanes thereon, a door mounted upon other movable means, devices operatively connected to each of said aeroplane and door mounting means, and mechanism for operating said devices to open said door and to remove the aeroplanes from the hangar as a unit.
- 45 19. In an aeroplane hangar, the combination of a plurality of compartments, a Z-shaped partition separating said compartments to permit aeroplanes on the respective sides thereof to be dovetailed together, and independent means for moving said planes from each of said compartments when a predetermined condition exists within said compartments.
- 50 20. In a device of the class described, the combination of a hangar, a plurality of trucks adapted to support flying machines, said machines being dovetailed to decrease the space required for storing said machines, and devices for removing said machines from said hangar and separating them a predetermined distance while moving from said hangar.
- 55 21. In an aeroplane hangar, the combination of a runway below the level of the floor of the hangar, trucks mounted in said runway provided with a platform substantially at the level of the floor of the hangar, adapted to receive and support aeroplanes, and a mechanism operatively connected to said trucks to remove said aeroplanes from said hangar.
- 60 22. In an aeroplane hangar, the combination of a door at the side of the hangar, trucks for mounting aeroplanes in staggered relation so that the wings of adjacent planes overlap each other and thereby reduce the space required for storing the planes, said trucks being adapted to move said planes sideways through said door, and devices for removing said trucks and planes mounted thereon from the hangar and to separate the adjacent planes, whereby said planes may be moved on and off the trucks transversely to the direction in which they are moved through the door after they are removed from the hangar.
